UNITED STATES PATENT OFFICE.

LOUIS KOSIOL, OF LOUISVILLE, KENTUCKY.

OVERFLOW AND WASTE FIXTURE.

SPECIFICATION forming part of Letters Patent No. 674,297, dated May 14, 1901.

Application filed September 1, 1900. Serial No. 28,804. (No model.)

To all whom it may concern:

Be it known that I, LOUIS KOSIOL, of Louisville, in the county of Jefferson and State of Kentucky, have invented certain new and useful Improvements in Overflow and Waste Fixtures; and I hereby declare that the following is a full, clear, and exact description thereof, reference being had to the accompanying drawings, which form part of this specification.

This invention relates to overflow and waste fixtures for sinks, bath-tubs, basins, &c., and is an improvement upon the fixture shown and described in United States Letters Patent No. 630,718, granted to me August 8, 1899, the object of which, as described in my said patent, was to enable the waste-pipe to be kept clean and clear, the trap to be cleaned when desired, and to prevent freezing thereof, and it also provided means whereby the water could be forced out of the trap at will, while the escape of waste water from the fixture was controlled and the inflow of sewer-gases prevented, and said device was also adapted to act as a plug to prevent the escape of the water from the fixture to which it was attached when desired.

The present invention embodies substantially all the advantages of the device shown in my aforesaid patent, and in addition has a constantly-maintained water seal to prevent entrance of gases into the building through the fixture, even when it is in such condition that water may readily escape therethrough.

The present invention therefore consists in the novel and improved construction and combination of parts hereinafter claimed, and illustrated in the accompanying drawings, in which—

Figure 1 is a sectional elevation of my improved waste device, showing the parts adjusted to permit escape of the water, while maintaining a water seal and preventing backflow of gases. Fig. 2 is a similar view showing the position of the parts when a permanent seal is formed or the position of the plunger and valve when adapted to be used as a piston.

A designates a basin or other fixture, to the outlet of which is suitably connected a tube D, to the lower end of which is attached a

waste-pipe d, which is held in place by coupling D', provided with a packing ring or washer d''. The upper end of the pipe d is flared to form a valve-seat d', upon which an inverted cup-valve E is adapted to seat. This valve is provided with a short stem e, its upper end being loosely confined in the recess f' of an annular or perforated plunger F, secured on the lower end of a valve-rod f. Encircling the valve-stem e is a spring e', located within the central recess f' of the perforated plunger F. One end of this spring bears against the head of the valve-stem e, and its other end is adapted to bear against the lower end of said recess. This spring, however, is not essential to the practical operation of the valve, but may be found advantageous to facilitate its operation.

The plunger F is provided with exterior packing f' to fit it tightly within the tube D and with a depending annular conoidal flange or extension F' on its lower portion surrounding the opening in the plunger. The lower end of flange F' depends into the cup-valve E, as indicated, and as the cup-valve is normally full of water the lower end of the annular flange F' will be submerged in the water in cup E and will form a water seal below plunger F, although water may readily descend through the plunger and overflow the valve E and thence escape, as is obvious. When the plunger is pushed entirely down, as shown in Fig. 2, the cup-valve E is pressed closely to the seat d', and the flange F' also fits closely in the valve E. The water seal can be constantly maintained, however, between the valve E and plunger F. On the outer end of the valve-rod f and within the basin is formed a circular handle C, and depending from the lower side thereof and parallel with the valve-rod are two depensions or rests c.

In the outlet of the basin or fixture A is fitted a strainer B, which, as shown, is preferably provided with holes b sufficiently separated and large enough to admit the rests c. The strainer is also provided with a series of small apertures, and obviously when the rests are above the strainer the valve is open, but when pushed down through the openings b' the valve is closed.

Instead of the tube D being connected di-

rectly to the fixture and the strainer fitted to the tube, as shown, the tube may be secured to an adjustable collar or coupling at the waste-opening. As shown, the waste-outlet 5 pipe may also be provided with an outlet d^4 below the valve-seat for the purpose of attaching a back vent. Of course it is understood that a swivel, as well as a straight outlet, may be employed, as illustrated by dotted 10 lines in Fig. 1.

When the plunger and valve are seated, as shown in Fig. 2, no water can escape from the fixture nor can any gas enter therethrough, as a double closure is formed between the 15 seat d' and valve E and between the valve E and flange F'. If the plunger is slightly raised, as indicated in Fig. 1, water can escape through the fixture, as is obvious, passing through plunger F and around the valve 20 E; but at the same time it will be observed that no gas can escape upwardly through the tube D, because of the water seal constantly maintained between the valve E and the flange F' of the plunger.

If the plunger and valve are raised to the 25 highest position and then suddenly depressed, the valve E will be forcibly seated against the plunger F, particularly if there be any water in the tube D, and these together will form 30 a tightly-fitting piston in the tube D, and the air, water, or other matter below this piston will be forced downward, and thus water or other obstacles below the piston and plunger can be forced out of the pipe.

Having thus described my invention, what 35 I therefore claim as new, and desire to secure by Letters Patent thereon, is—

1. In an overflow-fixture for sinks, &c., the 40 combination of a waste-tube, the plunger therein having a passage for the water, and a depending flange surrounding the passage; with the cup-valve suspended from and below said plunger and projecting above and around the lower edge of the flange, and 45 adapted to retain water to form a water seal

between the valve and plunger, substantially as and for the purpose described.

2. The combination of a tube attached to the outlet of the fixture, the valve-seat at the lower end of the tube, the movable plunger 50 in the tube having a water-passage and a depending flange surrounding such passage, and the cup-shaped valve suspended from said plunger and adjustable therewith within the tube and adapted to close the outlet when 55 the plunger is sufficiently lowered, and also to form with the flange a constant water seal when the plunger is raised, substantially as described.

3. The combination of the waste-tube, the 60 valve-seat at the lower end of said tube, the adjustable plunger within said tube and the plunger-rod; with the cup-shaped valve loosely suspended from said plunger and adapted to close the outlet when the plunger 65 is fully lowered, and to form with the flange a constant water seal when the plunger is raised, and means for holding the plunger in open position, for the purpose and substantially as described.

4. The combination of the water-fixture, the waste-tube connected therewith, the valve-seat at the lower end of said tube, the annular plunger within said tube tightly fitted therein provided with a water-passage and a 75 depending flange surrounding such passage, and the plunger-rod projecting into the fixture; with the cup-shaped valve loosely suspended from said plunger and adapted to close the outlet when the plunger is fully lowered and also adapted to form with the flange 80 a constant water seal when the flange is raised, for the purpose and substantially as described.

In testimony that I claim the foregoing as my own I affix my signature in presence of 85 two witnesses.

LOUIS KOSIOL.
